DOOR CARRIER

Daniel W. Shattuck, Indianapolis, Ind., assignor
to Universal Door Carrier, Inc., Indianapolis,
Ind., a corporation

Application July 9, 1948, Serial No. 37,873

7 Claims. (Cl. 212—4)

1

This invention relates to a door carrier.

The chief object of the present invention is to provide a door carrier that can be operated by one or more operators simultaneously and applied to a door for moving same from closing position to open position with a minimum of effort and practically regardless of door size and vice versa.

This invention is peculiarly applicable to handling of large doors for airplane hangars and the like although not necessarily restricted thereto. Such doors for example may be some thirty or more feet high and twenty or more feet wide so obviously are too large and too heavy for one man handling in an emergency. Such a hangar may be some hundred or so feet wide requiring the requisite number of door units.

A single carrier, as herein contemplated, is interchangeably associated with such doors for moving same from storage to closing position and vice versa. This carrier can be selectively associated with any one or a group of doors as desired and regardless of the position of the desired door in the complete closure comprised of a plurality of doors regardless of width.

The chief feature of the present invention resides in the construction of the basic unit of the door carrier.

A further feature resides in the door carrier comprising, when desired, a plurality of connected carrier units.

Still a further feature of the invention resides in the balanced construction of each carrier unit.

Other objects and features of the invention will be set forth more fully hereinafter.

The full nature of the invention will be understood from the accompanying drawings and the following description and claims:

In the drawings, Fig. 1 is a front elevation of a wide door with a triple unit carrier applied thereto.

Fig. 2 is a similar view of a narrower door with a dual unit carrier applied thereto.

Fig. 3 is a similar view of a dual door formation with a single unit carrier applied to one of the doors.

Fig. 4 is a vertical sectional view through a door, a frame therefor and the carrier applied thereto, the parts being shown in full lines as disposed just prior to door movement from the opening or just after the door has been moved into closing position, dotted lines indicating the position of certain of said parts when the door is free from its normal support and carried by the

2

carrier for movement to and from the door closing position.

Fig. 5 is an enlarged elevational view of the left hand end of the several parts shown in Fig. 4.

In Figs. 1 to 5 inclusive 10 indicates a lintel member. Projecting outwardly therefrom at spaced intervals are the brackets 11, see Fig. 4. Said brackets support a rail 12 parallel to the lintel member. Said brackets also include upwardly and outwardly faced hooks 13 as shown.

Referring to Fig. 4, 14 indicates a door member of suitable construction depending upon the use of the structure to which it is to be supplied. 15 indicates the entrance or threshold. 16 indicates a door frame carried bracket including the upwardly and outwardly directed notch 17 therein. The side of the door may include the locking pin 18 for holding the door closed when lowered and applied to the opening.

The upper end of the door 14 mounts supports 19 which support in offset relation relative to the door the hanger member 20. These are arranged in pairs, although not necessary so to do, but there are at least two to each door. Each

hanger, in the plate portion which is of inverted keystone outline, see Figs. 1 to 3, includes in its lower edge a notch 21. The upper portion 22 of plate 20 is turned upwardly and inwardly toward the door, see Fig. 4 and is slotted at 23 to take the hook portion 13.

The door carrier to which this invention is directed is rollably supported upon track 12 and has portions 39 adapted to hook under the plates 20 and seat in notches 21 thereof. Then when

said portions are elevated and moved outwardly from the door opening the door is elevated and moved outwardly. This frees the pins 18 of notches 17 and the tongues 22 of the hooks 13. When so freed, the door is carrier supported and can be moved with the carrier along the rail to where desired. Reverse movement is effected for door closing. In this instance gravity assists in locking the door in closed position at the hook 13 and notch 17 of plate 16.

Reference will now be had to Figs. 1 to 3 more particularly, wherein is illustrated several of the possible door and carrier combinations. In Fig. 1, 3A indicates a door with which is associated a three unit carrier designated 3C, each carrier unit being designated by the letter C and connected together by bar 3B as shown.

In Fig. 2, 2A designates a door with which is associated a two unit carrier 2C each carrier unit being designated by the letter C and connected by the common bar 2B. In Fig. 3 there are two

individual doors A disclosed and the single carrier unit C, selectively associated with either, is shown applied to the left hand door.

Having thus briefly described and illustrated several of the many combinations possible reference will again be had more particularly to Figs. 4 and 5, it being understood that each for the length of bar B or its omission, the carrier in each instance includes N like carrier units where N is a whole number. The door in each instance has applied thereto 2N plates 20 and each pair of plates is spaced apart as determined by the unit carrier and the pairs of plates are spaced apart as determined by the spacing between units of the carrier where N is greater than unity.

In said Figs. 4 and 5 the carrier unit is shown comprised of spaced end brackets 24 which pivotally support at 25 the roller or trolley frame 26 mounting one or more grooved wheels 27 which roll, at all times upon rail 12. The spaced end brackets each may comprise a box frame or the like and same are connected by member 28.

Depending from each box frame or the like is the rigid member 29. These at their lower ends are connected by member 30. Also at suitable intervals at one or more places the members 29 may be cross connected as indicated at 31. The result is a comparatively rigid base frame that is rollably supported by the track 12.

To each depending frame member 29 and at a predetermined distance from the top there is pivoted at 32 a link 33. Adjacent thereto and slightly lower thereon there is pivoted at 34 a strut member 35. These two are directed upwardly and oppositely from member 29. A link 36 is pivotally connected at opposite ends to the upper end of link 33 at 37 and to strut member 35 near its upper end at 38. Member 35 terminates in the hook 39 that engages in notch 21 of plate 20.

Depending from the pivotal connection 37 and pivoted thereto is a depending actuating member or arm 40. Its lower end is angled inwardly as indicated at 40a and is pivoted at 41 to an arm 42 pivoted at 43 in bracket 44 carried by member 29 near the lower end as at 45. As herein shown the pivoted end of arm 42 is connected as by member 46 to the corresponding end of the other arm of the unit. Also the free ends of arms 42 are connected together as at 47, in fact arms 42, member 46 and member 47 comprise a rectangular type actuating arm for a pair of spaced lifters.

The cross-bar portion 47 and arms 42 may comprise a single bar bent into U-shaped and welded at the ends to the tube 46. Bar 47 is suitably notched to provide spaced bolt holes whereby the cross-bars B between carrier units can be bolted thereto.

Hence one man can simultaneously operate light weight unwieldy doors or a plurality of operators can simultaneously operate the several units of a carrier.

Specific carrier unit operation is as follows: The carrier is rolled into place in front of the door to be moved. The cross-bar or handle 47 is then raised to slightly above the position shown in full lines in Fig. 4. This disposes hooks 39 below the plates 20. Then the handle is pulled downward (counter-clockwise). This raises the plates and with them the door 14. As the door is raised, pins 18 raise in slots 17 and then ride the upper inclined edges of same.

At the same time the raising of plates 20 causes the upper portions 22 to raise upwardly and outwardly the top of the door. Until the hooks 43 are free of plates 20-22 the door is still subject

to building structure restraint. When free of hooks 43 the door is further elevated and as handle 47 passes downwardly over center to the dotted line position the door is fully elevated, free of the building structure and its lower portion can bear against cross member 30. The carrier now can be moved with the carrier supported door along the track 12 to the desired position and the door then lowered into storage position in a manner the reverse of the aforesaid. To close the opening the door is picked up from the storage position, transported to the opening to be closed and deposited upon hooks 43 with pin 18 in slots 17. When lowered and released the door by its own weight moves inwardly to seal the opening.

While the invention has been illustrated and described in great detail in the drawings and foregoing description, the same is to be considered as illustrative and not restrictive in character.

The several modifications described herein as well as others which will readily suggest themselves to persons skilled in this art, all are considered to be within the broad scope of the invention, reference being had to the appended claims.

The invention claimed is:

1. In a free door closable structure having at least one free door with at least a pair of hanger plates thereon, a similar number of hooks disposed above the opening to be closed by that door, and an overhead rail, the combination therewith of a door carrier comprised of a pair of spaced trolleys rollable upon the rail, a pair of spaced depending supports disposed in a plane offset from the plane of trolley and rail, cross connections between the depending supports, a hook member pivoted upon each support, a link member pivoted thereon in offset relation to the first pivot, a second link pivotally connected to each of the hook members near the hook portion thereof and to the respective link members, a lever arm pivoted upon each of the support members near the lower end thereof, and a tie rod pivotally connected at opposite ends to the lever arms in spaced relation to the pivotal axis thereof and to the pivotal connection between the links.

2. A structure as defined by claim 1, wherein there is provided a cross-bar handle between the lever arms.

3. A structure as defined by claim 2 wherein the cross-bar handle and lever arms comprise a U-shaped member.

4. A structure as defined by claim 2 wherein a rectangular open type member comprises the said lever arms, the said cross-bar handle therebetween and a rigid connection between said lever arms substantially coincident with the pivotal axis of the arms.

5. A door carrier unit comprised of a rectangular elongated frame rollably supported at the upper end, a U-shaped handle-lever arm structure pivotally supported by the frame near the lower end, a rod extending upwardly from each arm and pivoted thereto in spaced relation to the ends of the arms, a triple link pivotally interconnected structure for each rod and disposed below the top of the frame and arranged generally in triangular position, one pivotal connection being coincident with the rod connection, the adjacent ends of the end links having independent pivotal connection to the frame, the link not directly connected to the rod having an

upwardly and outwardly directed hook-formed extension.

6. A door carrier comprised of a plurality of substantially identical units, each being as defined by claim 5, and means rigidly connecting the handle-lever arm structures together for simultaneous movement.

7. A door carrier as defined by claim 6 wherein means is provided connecting the frames together.
